CLOSURE FOR BOTTLE STOPPERS AND POURERS

Daniel M. Fox, Brooklyn, N. Y.

Application August 21, 1939, Serial No. 291,121

12 Claims. (Cl. 215—73)

This invention relates to a bottle stopper and pourer and particularly to a cover therefor which is attached to the pourer in a simple manner without the use of hinges, pins, or any other additional parts.

An object of this invention is to eliminate all metal parts for joining the cover to the pourer, thus doing away with the possibility of rust and corrosion.

Another object of this invention is to provide a simple construction for the cover and pourer head and a simple method of applying the cover to the head whereby it cannot readily fall off or be displaced from the pourer outlet opening.

A more specific object of this invention is to provide a one piece molded bottle pourer and tip construction for the head thereof and a specific complementary construction for the closure member so that it fits over the tip of the head in a particular manner to provide an efficient closure that stays in place, cannot readily fall off and eliminates the use of hinges.

The above and other important objects and advantages of this invention will become apparent as the description proceeds, reference being had to the accompanying drawing wherein:

Figure 1 is a side elevation of the bottle stopper and pourer and closure therefor constructed according to this invention;

Fig. 2 is a front elevation view of Figure 1;

Fig. 3 is an enlarged sectional view on the line 3—3 of Figure 1 showing the closure in the down position and illustrating the relative cross-sectional size of the head and opening in the closure member that fits on the head;

Fig. 4 is a sectional view similar to Fig. 3 taken higher up on the head at the point indicated by number 10 in Figure 1;

Fig. 5 is a view similar to Fig. 4 showing the position of the closure when being turned about the head to a position at right angles to Fig. 4 for removal of the closure off the head; and

Fig. 6 shows a modification of the closure where the frame of the opening that fits on the head is not split, the sectional view of the head being taken at the same place as Fig. 4.

Referring to the drawing, 11 indicates generally the bottle stopper and pourer. It comprises a stopper 12 and a spout 13 which communicates with the inside of the bottle by means of an opening through the spout (not shown).

The outlet of the spout provides a seat for a closure member 14 which fits on a head, generally indicated by 15, made integral with the

spout. The head extends upwards from the spout from point 16 of largest approximately rectangular cross-section to point 18 of smallest approximately rectangular cross-section. The cross-section of this portion of the head need not necessarily be rectangular. Any suitable cross-section other than circular may be used. From point 16 the head tapers off to flat sided tip 17 which is relatively wide and thin, as is shown on Figures 1 and 2.

The closure 14 may be of any suitable shape and size to cover the outlet of the spout. It has an extension 18 comprising two L shaped arms 19 which come together at 20 to form a rectangular frame of a cross-section slightly larger than cross-section 16. The closure 14 and arms 19 are made integral of any suitable material, preferably a plastic, that will allow some flexibility to arms 19 without breaking. The cross-section of the rectangle formed by arms 19 is so chosen that at its narrowest point it is slightly narrower than the widest point of the cross-section 16. Also, the widest side of the rectangle formed by arms 19 is slightly greater than the widest portion of the flat side of the head 15. It will thus be seen by referring to Fig. 5 that a slight force is necessary in order to spring the arms 19 slightly so that the closure 14 may be turned at right angles to its normal position. The closure may then be removed by passing it over the tip 17.

The operation for applying and removing the closure now becomes clear. From its normal seated position, the closure is lifted on the head 15 to the point 18 where it is turned at right angles (Fig. 5) and then lifted off past the tip 17. It is applied to the head by the reverse sequence of operations.

It will thus be seen that the closure of this invention may be readily applied to and be removed from the spout but it will not be displaced from its usual seated position by the jiggling or shaking of normal use.

In the modification shown by Fig. 6, the L shaped arms are joined together to form an unbroken rectangular space 21. This rectangular space must be wider at all points than the widest part of cross-section 16. The method of applying and removing this closure of this modification to the spout head is the same as in the first modification. This modification, however, is more apt to be displaced from its seated position by normal use than the first modification.

The closure of this invention will function to maintain the outlet of the spout closed when the

bottle stopper and pourer is in the upright position as shown on Figures 1 and 2. When tilted for pouring the closure will unseat and slide upwards on the head. It cannot fall off the head in normal use because of the tip 17. It will be noted that in pouring the closure moves completely out of the way of the outlet of the spout because of the backward curvature of the head relative to the outlet.

I do not wish to be limited to the exact showing and description as is herein disclosed, but all equivalents as may fall within the scope of the appended claims are meant to be included.

I claim:

1. In a bottle stopper and pourer, a spout having an outlet, a closure for the outlet, a support for maintaining the closure in its operative position comprising a head connected to the top of the spout of non-circular cross-section which varies from a maximum area at the joining point with the spout to a minimum at its top, an extension on the closure formed with an opening substantially similar to the cross-section of the head and slightly greater in area than the maximum cross-sectional area of the head, the head adapted to pass through the opening in the closure to support the closure loosely and to maintain it upon the spout.

2. In a bottle stopper and pourer, a spout having an outlet, a closure for the outlet, a support for maintaining the closure in its operative position comprising a head connected to the top of the spout of substantially rectangular cross section which varies from a maximum at the joining point with the spout to a minimum at its top, an extension on the closure formed with an opening of substantially rectangular cross-section and of a size slightly greater than the maximum cross-sectional area of the head, the head adapted to pass through the opening in the extension to support the closure loosely and to maintain it upon the spout.

3. In a bottle stopper and pourer, a spout having an outlet, a closure for the outlet, a support for maintaining the closure in its operative position comprising a head connected to the top of the spout, said head being of varying cross-section from a rectangular maximum area cross-section at its bottom which cross-section continually decreases in area as it goes up to a relatively wide, substantially flat sided tip at its top, said closure having an extension formed with an opening of substantially similar cross-section as that at the bottom of the head, said head adapted to fit into the opening of the extension in the closure to maintain the closure in seated position on the outlet of the spout, the narrowest side of the opening in the extension being smaller than the width of the flat sided tip on the head.

4. In a bottle stopper and pourer, a spout having an outlet, a closure for the outlet, a support for maintaining the closure in its operative position comprising a head connected to the top of the spout, said head being of varying cross-section from a rectangular maximum area cross-section at its bottom which cross-section continually decreases in area as it goes up to a relatively wide, substantially flat sided tip at its top, said closure having an extension formed with an opening of substantially similar cross-section as that at the bottom of the head, said head adapted to fit into the opening of the extension in the closure to maintain the closure in seated position on the outlet of the spout, the narrowest side of the opening in the extension being smaller

than the width of the flat sided tip on the head and the widest side of the opening in the extension being slightly larger than the width of the flat sided tip on the head.

5. In a bottle stopper and pourer, a spout having an outlet, a closure for the outlet, a support for maintaining the closure in its operative position comprising a head connected to the top of the spout, said head being of varying cross-section from an oblong rectangular maximum area cross-section at its bottom which cross-section continually decreases to a substantially square rectangular cross-sectional area near its top and then flattens to a relatively wide substantially flat sided tip, said closure having an extension formed with an opening of substantially similar shape as the cross-section at the bottom of the head, the head adapted to fit into the opening of the extension in the closure to maintain the closure in position on the outlet of the spout, the narrowest side of the opening in the extension being slightly wider than the widest part of the square rectangular cross-section of the head.

25 6. In a bottle stopper and pourer, a spout having an outlet, a closure for the outlet, a support for maintaining the closure in its operative position comprising a head connected to the top of the spout, said head being of varying cross-section from an oblong rectangular maximum area cross-section at its bottom which cross-section continually decreases to a substantially square rectangular cross-sectional area near its top and then flattens to a relatively wide substantially flat sided tip, said closure having an extension formed with an opening of substantially similar shape as the cross-section at the bottom of the head, the head adapted to fit into the opening of the extension in the closure to maintain the closure in position on the outlet of the spout, the narrowest side of the opening in the extension being slightly wider than the widest part of the square rectangular cross-section of the head and the widest side of the opening in the extension being slightly longer than the width of the flat sided tip on the head.

7. In a bottle stopper and pourer, a spout having an outlet, a closure for the outlet, a support for maintaining the closure in its operative position comprising a head connected to the top of the spout, said head being of varying cross-section from an oblong rectangular maximum area cross-section at its bottom which cross-section continually decreases to a substantially square rectangular cross-sectional area near its top and then flattens to a relatively wide substantially flat sided tip, said closure having two L shaped arms extending from it which come together to form a rectangular opening of substantially similar shape as the cross-section at the bottom of the head, the head adapted to fit into the opening formed by the L shaped members to maintain the closure in position on the outlet of the spout, the narrowest side of the opening formed by the L shaped arms being slightly narrower than the widest part of the square rectangular cross-section of the head.

8. In a bottle stopper and pourer, a spout having an outlet, a closure for the outlet, a support for maintaining the closure in its operative position comprising a head connected to the top of the spout, said head being of varying cross-section from an oblong rectangular maximum area cross-section at its bottom which cross-section continually decreases to a substantially

square rectangular cross-sectional area near its top and then flattens to a relatively wide substantially flat sided tip, said closure having two L shaped arms extending from it which come together to form a rectangular opening of substantially similar shape as the cross-section at the bottom of the head, the head adapted to fit into the opening formed by the L shaped members to maintain the closure in position on the outlet of the spout, the narrowest side of the opening formed by the L shaped arms being slightly narrower than the widest part of the square rectangular cross-section of the head and the widest side of the opening formed by the L shaped arms being slightly longer than the width of the flat sided tip on the head.

9. In a bottle stopper and pourer, a spout having an outlet, a closure for the outlet, a support for maintaining the closure in operative position comprising a head connected to the top of the spout of a varying non-circular cross-section, said cross-section being widest along a given line at the joining point with the spout and widest along a line substantially perpendicular to said given line at approximately the top of the head, an extension on the closure formed with an opening substantially similar to the cross-section of the head at the joining point with the spout, the head passing through the opening in the closure to support it.

10. In a bottle stopper and pourer, a spout having an outlet, a closure for the outlet, a support for maintaining the closure in operative position comprising a head connected to the top of the spout of varying substantially oblong cross-

section, said cross-section having its long axis along a given line at the joining point with the spout and its long axis along a line substantially perpendicular to the given line at approximately the top of the head, an extension on the closure formed with an opening substantially similar to the cross-section of the head at the joining point with the spout, the head passing through the opening in the closure to support it.

11. In a bottle stopper and pourer, a spout having an outlet, a closure for the outlet, a support for the closure, said closure in its operative position being slidably mounted on said support while locked against removal therefrom in any plane parallel to its operative position, said closure comprising a body portion for closing the outlet of the spout and an extension having an opening therein through which the closure support passes, said opening being of non-circular cross section and determined by two arms which extend from the body portion of the closure and envelop said support, said arms being adapted to provide an enlarged opening upon rotation of the closure relative to its operative position.

12. In a bottle stopper and pourer, a spout having an outlet, a closure for the outlet, a support for the closure, said closure in its operative position being slidably mounted on said support while locked against removal therefrom in any plane parallel to its operative position and removable therefrom by rotation relative to its operative position, said closure comprising a body portion for closing the outlet and arm portions for enveloping the said support.

DANIEL M. FOX.
